UNITED STATES PATENT OFFICE.

ROBERT E. KIMBALL, OF CLEVELAND, OHIO.

BLADE-SHARPENER.

1,152,321.

Specification of Letters Patent. Patented Aug. 31, 1915.

Application filed November 10, 1913. Serial No. 800,023.

To all whom it may concern:

Be it known that I, ROBERT E. KIMBALL, a citizen of the United States, residing at Cleveland, in the county of Cuyahoga and 5 State of Ohio, have invented a certain new and useful Improvement in Blade-Sharpeners, of which the following is a full, clear, and exact description.

This invention relates to blade sharpeners 10 and particularly to a device for sharpening knife blades.

The main object of the present invention is to provide an inexpensive sharpener in the form of a household article, by means 15 of which a knife or other blade may be quickly and effectively sharpened to as fine an edge as desired, and with a bevel which is uniform on both sides of the blade, and from one end of the blade to the other.

20 The sharpener which I have provided is of such a nature that it may be used in any household and in its operation does not require any special or particular skill, such as required with a hand operated steel, al- 25 though the blade is sharpened in much the same manner as with a hand operated steel when held properly.

This device includes a suitable blade holder 30 and a movable holder for the sharpening means, preferably two sharpening steels which are so mounted and actuated as to alternately move over and grind or cut opposite sides of the blade, the steels each engaging the blade near one end and leaving 35 the same at the other end, and each steel while engaging the blade passing through a plane which intersects the plane of the knife at a certain angle, which is uniform at all points so as to produce a uniform bevel.

40 My invention may be briefly summarized as consisting in certain novel combinations and arrangements of parts which will be described in the specification and set forth in the appended claims.

45 Although my invention may be modified considerably in numerous respects, I have shown the preferred construction in the drawings, in which—

Figure 1 is a side view of the sharpener 50 attached to the edge of a table or other suitable support, and showing a knife with its blade in position to be sharpened. Fig. 2 is a top plan view of the same. Fig. 3 is an enlarged view partly in section, and

partly in elevation, the section being taken 55 substantially through the driving spindle. Fig. 4 is a sectional view substantially along the line 4—4 of Fig. 3. Fig. 5 is a sectional view substantially along the line 5—5 of Fig. 3; and Fig. 6 is a view of the sharpener 60 as viewed from a point looking toward the blade in the plane thereof,—the blade and part of the blade clamp being shown in section.

Referring now to the drawings, it will be 65 seen that the sharpener includes a bracket member 10 which can be secured by a clamp 11 to the edge of a table or other suitable support 12. Near one end of the bracket is a plate 13 to which is adjustably secured a 70 clamp 14 for a blade 15 to be sharpened. The clamp consists of two members 14^a and 14^b which are connected by pivotal pins 16 and stand at an angle with reference to the axis of revolution of the steels, so that the 75 blade held between the lower edge portions of the clamping members will be supported in operative position somewhat as shown in the drawings. That is, the blade will be in a vertical plane with its edge downward, 80 and will be at an angle of nearly 45° with respect to the horizontal support 12 to which the sharpener is secured. The clamp is adjustably secured to the plate 13 by means of a fixed pivotal pin or screw 17 and an adjustable holding screw 18 which extends through a slot in the end of one of the 85 clamping members.

Near the opposite end of the bracket is a clamping boss 19, which is secured to a fixed 90 sleeve 20 provided with a bushing 20^a in which is journaled a horizontal shaft 21 constituting the main operating shaft whose axis intersects at right angles the vertical plane in which the blade is held.

95 The shaft 21 which may be held from endwise movement in the sleeve in any suitable manner, is provided at its forward end with an extension consisting of a member 22 which is secured to the end of the shaft and 100 is provided with means,—in this case a crank or handle, for rotating the shaft 21 and the shaft extension 22, about the axis of the shaft. The shaft extension or extension member 22 is offset laterally from the 105 shaft axis, and this offset portion has a flat face to which is pivotally secured by a central pivotal pin or screw 23, a block 24 con-

stituting a holder for the sharpening members, the said holder having its longitudinal axis at an angle to the axis of rotation of shaft 21. The pivotal axis of the holder 24 lies in the vertical plane of the knife or blade when supported by the clamp in operative position. That is, the plane of the blade intersects the block or holder at its pivotal axis.

10 Mounted in the holder 24 and extending outwardly in opposite directions therefrom and at right angles to the longitudinal axis of the holder are two parallel spindles 25 which are mounted in the end portions of 15 the holder and are equally spaced from the central pivotal axis of the latter. These spindles are adapted to be rotated about their axes and each is held from endwise movement in the holder by a collar 25^a secured to the spindle on one side of the holder and by a washer 25^b at the inner end of the spindle held in place by a removable screw 25^c extending into the end of the spindle.

25 The spindles carry at their outer ends sharpening steels 26 which are removable and in this instance, are provided at their ends with threaded studs 26^a which are screwed into threaded sockets in the ends 30 of the spindles. As will appear presently, when the steels are revolved about the axis of the main shaft, they alternately engage and slide over the opposite side edges of the 35 blade so as to sharpen the same. As the steels are revolved by turning the crank, they are also slowly rotated about their own axes by the following means. It will be observed that extending lengthwise through the block or holder 24 at one side of the center of the latter and contiguous to the inner 40 ends of the steel holding spindles 25 is a threaded pin or screw 27 which extends through the holder and through a boss 28 at the inner end of the holder, and has at its 45 inner end a head 27^a in the form of a wheel or disk which rolls, and thus turns on an annular radial flange or shoulder 29 on the adjacent end of the bearing sleeve 20 through which the shaft extends. When the 50 head 27^a rolls and turns on the flange 29, it, of course, rotates the screw 27. The rotary movement of the screw 27 is transmitted to the steel carrying spindles 25 by providing on each of the spindles and on that part of the spindle which extends into the holder 24, teeth 30 which engage and coöperate with the threads of the screw, so that the two constitute, in effect, a form of worm 55 gearing.

60 The annular head 27^a of the screw 27 is pressed yieldingly against the flange 29 by a coil spring 31 which surrounds an adjustable pin 32 extending through a lug on the boss 28, and through the holder 24—the pin 65 32 having at one end a head and at the op-

posite end a nut, the position of which can be adjusted by turning the head so as to vary the normal tension of the spring 31.

When the steels are revolved about the axis of the shaft 21 by turning the crank 23 and with no blade in the clamp 14, the head 27^a on the end of the screw 27 rolls around the flange 29 on the end of the bearing sleeve, and the block or holder 24 is thus maintained in fixed position with reference 75 to the holder, and the steels describe two conical surfaces, the outer extremities of which intersect each other. It will be apparent that as long as the head 27^a engages the flange 29, while the crank is being 80 turned and the steels revolve, the steels will be turned slowly about their axes.

Assuming now, that a knife is placed in the clamp and is held as shown in Fig. 1, when the steels are revolved by turning the 85 crank, one of the steels will slide and move along one edge of the blade, and the other steel will slide or move along the opposite edge of the blade, and, in so doing, will sharpen the blade, producing at the edge of 90 the same a bevel, the angle of which depends upon the distance between the base portions of the steels and the shortest distance between the blade and the axis about 95 which the steels are revolved. Each steel will first engage the blade near its base or far end, the outer end of the steel first engaging the blade, and will remain in engagement therewith until the steel slides off the 100 opposite end of the blade, the steel gradually moving outwardly with reference to the blade. That is, the point of contact of the steel with the blade gradually approaches the inner end of the steel until the right angle position is reached, as shown by 105 dotted lines in Fig. 1. This outward movement of the steel with reference to the blade, as the steel is moved along the edge of the blade, is of importance, as it is a factor in the securing of an extremely sharp and 110 effective cutting edge. As the outer end of the steel first engages the blade and rides up onto the edge portion thereof, the block or 115 holder 24 is rocked about its pivotal pin, and the roller or head 27^a of the screw 27 moves out of engagement with the flange 29, so that said roller and flange no longer control the path of movement of the steel, but the latter, as long as it is in engagement 120 with the blade, describes or moves in a plane which intersects the plane of the blade of the knife on a line, and thus the steel produces a bevel which is uniform from the point at which the steel first engages the 125 blade to a point at which it leaves the blade. This same bevel is provided on both edges of the blade, one steel passing along one side of the blade, and the other steel then passing along the opposite side of the blade, and both engaging the same at the same 130

angle, and both being held or pressed against the blade with substantial uniform pressure by the spring 31.

While the steel is passing along the edge 5 of the blade, the roller or head 27^a of the screw 27 is out of engagement with the flange 29, and in consequence, during such time, the steels are not rotated, but, as soon as the steel passes off the knife, the head 10 27^a again engages the flange 29 and rotation of the steels again begins. Consequently, during the actual use of the sharpener, the steels are very slowly intermittently rotated, so that a new point of contact is being constantly 15 presented to the blade. The steel will therefore wear uniformly, so that uniform cutting or sharpening effect is obtained throughout the period of engagement of the steel on the blade. It will be understood, 20 of course, that when the steels are considerably worn from use and are no longer very effective for sharpening purposes, they can be replaced with new steels.

The adjustment of the clamp relative to 25 the blade 13 permits the adjustment or variation in the bevel or angle of the bevel which is produced on the edge of a blade. For example, if the clamp 14 is positioned so that the point of the blade is at a greater 30 distance from the steel holder or axis about which the steels are revolved, the steels will produce a more acute bevel or edge. If, on the other hand, the clamp is adjusted so that the point of the blade is brought nearer 35 to the axis about which the steels are revolved, the steels will produce a more obtuse bevel or angle at the edge of the blade.

It will be obvious that certain changes 40 may be made in the details of construction without departing from the spirit and scope of my invention.

Having thus described my invention, what I claim as new and desire to secure by Letters Patent is:

45 1. In a blade sharpener, a holder for a blade, a rotary shaft, a sharpening tool extending outwardly therefrom and adapted to revolve about the axis of the shaft, and to engage one side of the blade in its movement, so as to form a beveled edge thereon, and yieldable means for pressing the tool against a blade supported in the holder.

50 2. In a blade sharpener, a holder for a blade, a rotary driving shaft, a sharpening tool extending outwardly therefrom and adapted to revolve about the axis of the shaft and to engage and move along one side of the blade so as to form a beveled edge thereon, said sharpening tool being 55 movably supported by said shaft so that the position of the latter will change with reference to the shaft when the tool engages a blade supported in the holder.

60 3. In a blade sharpener, a blade holder, a pair of sharpening tools, means for revolv-

ing the tools so that they will alternately slide along opposite sides of a blade supported in the holder, and in planes at angles to the plane of the blade, so as to produce a beveled edge.

70 4. In a blade sharpener, a blade holder, a pair of sharpening tools, means for revolving the tools so that they will alternately slide along opposite sides of a blade supported in the holder, so as to produce a bevelled edge.

75 5. In a blade sharpener, a blade holder, a pair of sharpening tools, means for revolving the tools so that they will alternately slide along opposite sides of a blade supported in the holder, and in planes at angles to the plane of the blade, so as to produce a beveled edge, and means for causing yielding pressure between the tools and blade.

80 6. In a blade sharpener, a blade holder, a revolvable sharpening tool, means for supporting the tool so that it will engage and slide along a blade supported in the holder, and at the same time move endwise relative to the blade and means for rotating the 85 said supporting means.

85 7. In a blade sharpener, a blade holder, a rotary shaft, a sharpening tool adapted to be revolved by said shaft so as to slide along the side of the blade with the blade engaging surface of the tool at an angle to the plane of the blade, and a holder for the 90 tool supported by said shaft and movable relative thereto.

95 8. In a blade sharpener, a blade holder, a shaft, a tool holder supported by the shaft and pivotally connected thereto, a sharpening tool projecting laterally from the holder, and means for rotating the shaft so as to revolve the tool to cause the same to 100 engage and move along one side of a blade supported in the blade holder.

105 9. In a blade sharpener, a rotary support, a member pivoted thereto, and a pair of sharpening tools supported by said member 110 and projecting laterally therefrom.

110 10. In a blade sharpener, a blade holder, a rotary shaft, a pivoted tool supporting member carried by said shaft, and a pair of sharpening tools carried by said member so 115 as to engage and move along opposite sides of a blade supported in the blade holder and produce a beveled edge thereon.

115 11. In a blade sharpener, a blade holder, a rotary shaft, a pivoted tool supporting member carried by the shaft, a sharpening tool projecting from said member so as to engage and move along the side of the blade when revolved by the rotation of the shaft, and means acting on said member to press 120 the tool yieldingly against the blade.

125 12. In a blade sharpener, a blade holder, a rotary shaft, a pair of sharpening tools pivotally supported by said shaft and projecting laterally with respect thereto so that 130

when the shaft is rotated, said tools describe two surfaces which intersect each other.

13. In a blade sharpener, a blade holder, a rotary shaft, a pair of sharpening tools loosely connected to said shaft and projecting laterally therefrom, means constraining said tools to normally describe two intersecting conical paths when the shaft is rotated and for permitting said tools to move out 10 of said paths when engaging a blade supported in the holder.

14. In a blade sharpener, a blade holder, a rotary shaft, a sharpening tool supported by said shaft and projecting outwardly 15 therefrom normally at a fixed angle with respect thereto, and means permitting the angle of the tool with reference to the shaft to change as the tool moves along the side of a blade supported in the holder.

15. In a blade sharpener, a blade holder, a rotary shaft, a tool holder supported by the shaft, and pivoted thereto at a central point located in the plane of a blade supported in the blade holder, a pair of sharpening tools supported by the tool holder and projecting outwardly from opposite sides thereof, and located equal distances from the pivotal axis of the tool holder, said tools normally projecting at angles to the 25 axis of the shaft such that when the shaft is rotated, the tools will engage opposite sides of the blade and produce a beveled edge thereon.

16. A blade sharpener comprising a blade holder, a rotary shaft, a sharpening tool supported by the shaft and projecting laterally with respect thereto so that when said shaft is rotated, the tool is revolved about the axis of rotation and slides along the side of a 30 blade mounted in the holder, with the blade engaging surface of the tool passing in a plane which is at an angle to the plane of the blade.

17. In a blade sharpener, a shaft, a sharpening tool supported by the shaft and projecting laterally with respect thereto, means 45 for rotating the shaft so as to revolve the

tool about the axis of the shaft, and means for causing the tool to rotate on its axis as it is revolved.

18. A blade sharpener comprising a sharpening tool, a rotary support for the tool from which the tool projects laterally, and means for rotating the tool about its axis when the support is rotated to revolve the 55 tool about a different axis.

19. In a blade sharpener, a rotary support, a sharpening tool projecting laterally therefrom so as to be revolved by the 60 rotation of the support, and means connected to said tool for rotating the same about its axis when the tool is revolved.

20. A blade sharpener comprising a rotary support, a member pivoted thereto, a sharpening tool carried by said member and projecting laterally with respect to the support, so that the tool is revolved by rotating the support, and means for rotating the tool about its axis when said tool is revolved.

21. A blade sharpener comprising a rotary shaft, a pivoted tool holder carried by 75 said shaft, a tool carried by said holder and projecting laterally with respect to the shaft so as to be revolved when the shaft is rotated, and means for rotating the tool about its axis when the tool is revolved, comprising two co-operating frictional driving members including a rotating part operatively connected to the tool.

22. In a blade sharpener, a holder for a blade, a rotary shaft, a sharpening tool extending outwardly therefrom and adapted to revolve about the axis of the shaft and to engage the blade so as to form a beveled edge thereon, and means for causing yielding pressure between the tool and the blade.

In testimony whereof, I hereunto affix my signature in the presence of two witnesses.

ROBERT E. KIMBALL.
